QUICKLY ADJUSTABLE VISE HAVING
SAFETY STOPDavid Firth, South Bend, Ind., assignor to Dodge
Manufacturing Corporation, Mishawaka, Ind.,
a corporation of Indiana

Application June 23, 1950, Serial No. 169,836.

7 Claims. (Cl. 81—30)

1

This invention relates to bench vises of the quickly adjustable type.

In a vise of the type referred to, the movable jaw member can be quickly slid to a position of rough adjustment relative to the stationary member, and can then be screw-forced inwardly or toward the stationary jaw member to effect clamping of an interposed work piece. The mechanism of the vise includes a clamping screw and means whereby rotation of the screw in one direction will establish a condition for screw-forcing the movable member inwardly or rearwardly by continued rotation of the screw in said one direction. By a reverse rotation of the screw, a release condition is established, freeing the movable member for unimpeded sliding movement. Thus the operator, after quickly adjusting the relationship of the vise jaws to accommodate an interposed work piece, or after pushing the movable jaw against a work piece held against the stationary jaw, can effect clamping by rotating the screw in the proper direction, and thereafter he can release the vise from clamping action by a reverse turn of the screw, whereupon he can draw the movable jaw member forward and again push it back to another position of rough adjustment or against a work piece held against the stationary jaw.

An example of a vise of the type aforesaid is shown in patent to Zitner, No. 2,464,630 dated March 15, 1949.

The vise shown in said Zitner patent, and other prior vises of the quickly adjustable type, can be fully closed by shoving the movable jaw member inwardly or rearwardly to a position jam against the stationary jaw. Hence in the use of such prior vises, there is opportunity for getting fingers mashed by suddenly pushing the movable member inwardly while inadvertently extending one's fingers into the gap between the jaws. Such an accident might happen, for example, by pushing the movable member home with the hand so placed thereagainst that the fingers overlie the movable jaw and extend into the gap between the jaws.

To obviate or minimize opportunity for such mishaps, the present invention provides a vise of the quickly adjustable type with means to limit quick, rearward movement of the movable jaw member, while allowing subsequent rearward movement thereof by screw-operation. The rearward movement imparted to the movable jaw member by simply pushing it inwardly, as distinguished from the rearward movement imparted thereto by operation of the clamping screw, may be referred to as its free sliding movement rearwardly. At the limit of such free sliding movement of the movable member rearwardly, a substantial gap will exist between the vise jaws, which gap may be wide enough to ac-

commodate a person's fingers, thus preventing mashing or injury of the fingers if extended into the space between the jaws while the movable member is pushed inwardly by hand as far as it can be so pushed.

A further feature of the invention is a specific improvement upon the vise mechanism of said Zitner patent with respect to the nut and pawl thereof and manner of supporting the clamping screw.

In the accompanying drawings, there is shown for illustration an embodiment of the invention in a vise of generally similar character and construction to that disclosed in said Zitner Patent No. 2,464,630.

Fig. 1 is a longitudinal sectional view of the illustrative vise, showing the mechanism thereof in condition for free sliding of the movable jaw member, said member being shown at the limit of its free sliding movement rearwardly.

Fig. 2 is a fragmentary sectional view showing the vise mechanism in condition for screw-forcing the movable jaw member inwardly or rearwardly to effect clamping action.

Fig. 3 is a section on the line 3—3 of Fig. 1, looking forward as indicated by the arrows.

Fig. 4 is a section on the line 4—4 of Fig. 2, looking rearwardly as indicated by the arrows.

Referring to the drawings, the movable jaw member 1 is formed with a rearwardly extending shank 2 slidably fitted in a guide passage therefor in the stationary jam member 3, whereby said movable member is supported and guided by said stationary member. The shank 2 is chambered and open at its bottom for the major portion of its length, being shown as inverted U-shaped in cross section. The stationary member 3 is formed with a base 4 adapted to be secured on a work bench or other support. Fixed in a longitudinal groove in said base is a ratchet bar 5 for engagement by a detent or pawl hereinafter referred to.

Swiveled to the movable member 1 and extending into its chambered shank 2 is a screw-threaded shaft 6, shown journaled in the front end wall 7 of said member and held against longitudinal displacement relative thereto by the enlarged shaft-head 8 in abutting relation to the outer face of 7 and a collar 9 fixed on said shaft in abutting relation to the inner side of 7. Said screw-threaded shaft 6 is hereinafter referred to as the clamping screw. The threaded portion thereof is engaged by a correspondingly interiorly threaded non-rotatable nut 10 slidably fitted in the shank 2. Said clamping screw together with the nut 10 is movable with the member 1 and its shank 2 as a unit. However, the nut 10 can be shifted axially relative to 2 by rotating the clamping screw by its operating handle 11.

Associated with the nut 10 is a detent cooperable with the ratchet bar 5 to hold the nut against forward shifting relative to the shank 2. Said detent is shown as a massive pawl 12 having a tooth 13 for engaging the ratchet bar. The teeth of said ratchet bar are arranged as shown to present abrupt rear faces for engagement by the pawl tooth 13. The pawl 12 is pivotally mounted in the shank 2 on a transverse pin 14 carried by said shank. To allow movement of the shank relative to the pawl, the pin 14, having its ends fixed in the opposite side walls of said shank, extends through a longitudinal slot 15 in the pawl. In virtue of said slot, the pawl is pivotally and longitudinally shiftably mounted relative to the shank 2.

The upper part of the pawl 12 is U-shaped in longitudinal section, as shown in Figs. 1 and 2, to provide a recess 16 in which the nut 10 is arranged, the ends of the nut being adjacent to end walls of said recess formed by the upwardly extending parts 17 and 18 of the pawl. Said parts 17 and 18 are U-shaped in cross section, as shown in Figs. 3 and 4, to accommodate the screw 6 with sufficient clearance to prevent interference by the screw with pivotal movement of the pawl. The parts 17 and 18 may be considered as comprising each a pair of arms between which the screw extends and with which the nut coacts to control the pivotal movement of the pawl.

As appears from Figs. 1 and 2, the nut 10 is somewhat shorter than the distance between the front and rear pawl arms 17 and 18, and the nut and pawl are so shaped that the pawl can be rocked between the positions shown in said figures, or into and out of engagement with the ratchet bar 5. Such rocking is effected by slightly shifting the nut 10 in opposite directions, this being accomplished by rotating the screw 6 in opposite directions.

When the pawl 12 is disengaged from the ratchet bar 5, the movable jaw member 1 is freely slideable in either direction, wherefore it can be quickly pulled forward and then pushed back to a position against a work piece held against the stationary jaw. Then, by rotating the screw 6 in a right hand direction, the nut 10 can be moved forward against the pawl arms 17, thereby rocking the pawl into engagement with the ratchet bar. This anchors the nut against further forward movement relative to the shank 2. Hence by continued rotation of the screw in said direction, the movable jaw member 1 can be screw-forced inwardly to effect clamping of the work piece, such movement being permitted by the slot 15 for the pawl pivot pin 14. By a reverse rotation of the screw, the nut can be moved rearwardly against the pawl arms 18, thereby rocking the pawl out of engagement with the ratchet bar. This establishes a release condition and frees the movable jaw member for unimpeded sliding.

The illustrative structure as thus far described is substantially similar to that disclosed in the Zitner patent aforesaid, though somewhat simpler in design and embodying a specific improvement in that the screw 6 of the illustrative structure is supported within the shank 2 by the nut 10 which in turn is supported by the pawl 12 from the pivot pin 14, the pawl and nut being so shaped that the pawl in all positions thereof supports the nut. In the position shown in Fig. 1, and in moving therefrom to the position shown in Fig. 2, the pawl supports the nut by

engagement of the pawl arms 17 with the vertical flat front end face of the nut and engagement of the pawl arms 18 with the inclined surface 19 of the rear end face of the nut, and by resting of the front end of the nut on the flat bottom of the pawl recess 16 in which the nut is accommodated. In the position shown in Fig. 2, the nut rests upon the then horizontal flat bottom of the recess.

For limiting free sliding movement of the movable jaw member rearwardly, a fixed stop 20 is arranged in the path of rearward travel of the pawl 12 or a shoulder 21 thereon. In the illustrative structure, said stop 20 is provided by the head of a screw which secures the ratchet bar 5 in place, and said shoulder 21 is formed by the forward end wall of a longitudinal groove 22 in the under side of the pawl, into which groove the stop 20 extends. Said groove is open at its rear end to allow travel of the pawl with member 1 and nut 10 to a forward position beyond said stop, and to permit the stop to enter the groove when the movable unit is again pushed rearwardly.

When the pawl 12 is disengaged from the ratchet bar, the movable jaw member 1 can be pushed inwardly or rearwardly by pressure of the hand thereagainst until the shoulder 21 strikes the stop 20, whereupon such movement will be stopped, since the member 1 is connected by the screw to the nut which is now held by the pawl against rearward movement. However, the screw can now be rotated in the direction to shift the nut forwardly, thereby rocking the pawl from the position shown in Fig. 1 to that of Fig. 2, and by continuing rotation of the screw in said direction the movable member 1 can be moved inwardly to effect clamping of a work piece between the jaws, such screw-forcing of the member 1 inwardly being allowed by the slot 15 for the pawl pivot pin 14.

It will be observed that when the movable jaw member is pushed inwardly as far as it can be pushed by pressure of the hand thereagainst, a substantial gap exists between the vise jaws, which is intended to be wide enough to prevent mashing a person's fingers extended between the jaws as the movable member is quickly pushed inwardly.

If movement of the pawl 12 from the position shown in Fig. 1 to that of Fig. 2 should be resisted by engagement of the shoulder 21 with the stop 20, as shown in Fig. 1, then the operator, as he turns the screw in a direction to move the nut 10 forwardly, may exert a slight forward pull on the screw, which will cause a slight forward shifting of the movable unit, thereby separating the shoulder 21 from the stop 20 sufficiently to enable the pawl to be easily moved on its pivot pin from the position of Fig. 1 to the Fig. 2 position.

It will be understood that the invention is not intended to be limited to the particular embodiment thereof herein shown and described, which is susceptible of modifications in form and details of construction without departing from the principle of the invention.

I claim:

1. A quickly adjustable vise comprising movable and stationary jaw members, a fixed ratchet bar, mechanism carried by and movable as a unit with the movable member comprising a clamping screw swiveled to said member, a non-rotatable axially shiftable nut engaging said screw, and a pivotally mounted pawl operatively connected to said nut and movable into and out of engage-

ment with said ratchet bar by shifting the nut in opposite directions by rotating the screw in opposite directions, said pawl when engaging the ratchet bar holding the nut from forward movement and when disengaged freeing the movable member for free sliding movement, the pivot of said pawl being in fixed relation to one of said pawl and movable member and shiftable longitudinally relative to the other, and a fixed stop on said stationary jaw member cooperable with said pawl for limiting rearward travel thereof, thereby limiting free sliding rearward or inward movement of the movable member while allowing subsequent rearward movement thereof by operation of the screw.

2. A quickly adjustable vise, according to claim 1, having a screw securing said ratchet bar in place and having a longitudinal groove in the under side of said pawl, said groove being closed at its forward end to provide a shoulder and being open at its rear end, said stop being provided by the head of said screw arranged in the path of rearward travel of said shoulder.

3. A quickly adjustable vise, according to claim 1, having a longitudinal groove in said pawl, said groove being closed at its forward end to provide a shoulder, and having said stop projecting into said groove in the path of rearward travel of said shoulder.

4. A quickly adjustable vise comprising movable and stationary jaw members, a fixed ratchet bar, mechanism carried by and movable as a unit with the movable member comprising a clamping screw swiveled to said member, a non-rotatable axially shiftable nut engaging said screw, and a pivotally mounted pawl operatively connected to said nut and movable into and out of engagement with said ratchet bar by shifting the nut in opposite directions by rotating the screw in opposite directions, said pawl when engaging the ratchet bar holding the nut from forward movement and when disengaged freeing the movable member for free sliding movement, the pivot of said pawl being in fixed relation to said movable member and said pawl being longitudinally shiftable relative to said movable member, and a fixed stop mounted on the stationary jaw member adjacent the rear end of said ratchet bar and cooperable with said pawl for limiting rearward travel thereof, thereby limiting free sliding rearward or inward movement of the movable jaw member while allowing subsequent rearward movement thereof by operation of the screw.

5. A quick-action vise comprising a relatively movable jaw member having a rearwardly extending chambered shank, a relatively stationary jaw member having a guide-way for said shank and having a fixed longitudinally disposed ratchet bar, a longitudinally disposed clamping screw swiveled to said movable member and extending into said shank, a non-rotatable axially shiftable nut engaging said screw and slidably in said shank, a pawl pivotally and longitudinally shiftable mounted in said shank and operatively connected to said nut and movable thereby into and out of engagement with said ratchet bar by shifting the nut in opposite directions by rotating the screw in opposite directions, said pawl when engaging the ratchet bar holding the nut against forward movement and when disengaged freeing the movable member for free sliding movement, and a fixed stop on the stationary jaw member cooperable with said pawl to limit its

rearward travel, thereby limiting rearward travel of the nut and free sliding rearward movement of the movable jaw member while allowing further rearward movement of said member by operation of the screw.

6. A quick-action vise comprising a relatively movable jaw member having a rearwardly extending chambered shank, a relatively stationary jaw member having a guide-way for said shank and having a fixed longitudinally disposed ratchet bar, a longitudinally disposed clamping screw swiveled to said movable member and extending into said shank, a non-rotatable axially shiftable nut engaging said screw and slidably in said shank, a pawl pivotally and longitudinally shiftable mounted in said shank and operatively connected to said nut and movable thereby into and out of engagement with said ratchet bar by shifting the nut in opposite directions, said pawl when engaging the ratchet bar holding the nut against forward movement and when disengaged from the ratchet bar freeing said movable member for free sliding movement, the screw and nut and pawl being movable as a unit with said movable member when so freed, the pawl and nut being so operatively connected as to allow only slight axial movement of the nut relative to the screw and slight rocking movement of the pawl relative to the nut, and a fixed stop on said stationary jaw member arranged for cooperation with said pawl to limit its rearward travel, thereby limiting free sliding rearward or inward movement of the movable jaw member while allowing further rearward movement thereof by operation of said screw.

7. A quick-action vise comprising a relatively movable jaw member having a rearwardly extending chambered shank, a relatively stationary jaw member having a guide-way for said shank and having a fixed longitudinally disposed ratchet bar, a longitudinally disposed clamping screw swiveled to said movable member and extending into said shank, a pawl formed with a recess, means operatively mounting the pawl within said shank for engagement and disengagement with said ratchet bar including a longitudinal slot in said pawl and a pivot pin fixedly carried by said shank and extending through said slot, and an axially shiftable non-rotatable nut in threaded engagement with said screw and slidably engaging said shank and extending into said pawl recess, the nut, upon certain turning movements of the screw, being slightly shiftable within said pawl recess to engage the pawl on either side of its pivotal mounting to rock the pawl in either direction for engagement and disengagement with said ratchet bar, and a fixed stop on said stationary jaw member in the path of rearward travel of said pawl, for the purpose described.

DAVID FIRTH.
